UNITED STATES PATENT OFFICE.

NIKOLA TRBOJEVICH, OF HIGHLAND PARK, MICHIGAN, ASSIGNOR TO GLEASON WORKS, OF ROCHESTER, NEW YORK, A CORPORATION OF NEW YORK.

METHOD OF FORMING SPIRAL BEVEL GEARS.

Original No. 1,465,150, dated August 14, 1923, Serial No. 528,511, filed January 8, 1922. Application for reissue filed March 14, 1925. Serial No. 15,668.

To all whom it may concern:

Be it known that I, NIKOLA TRBOJEVICH, formerly a subject of the King of Yugoslavia, but now a citizen of the United States, residing at Highland Park, in the county of Wayne and State of Michigan, have invented certain new and useful Improvements in Methods of Forming Spiral Bevel Gears, of which the following is a specification, reference being had therein to the accompanying drawings.

This invention relates to the manufacture of gears and particularly to the manufacture of gears from conical gear blanks. In the present state of the art, one method which is extensively used in the manufacture of spur gears is known as "hobbing" and consists in cutting the teeth of the gear by a helical cutter, continuously rotated in timed relation to a rotating gear blank and also given a movement of translation across said blank. Such hobbing process is not, however, applicable to the cutting of bevel gears of conventional form, for the obvious reason that neither the teeth nor the interdental spaces of bevel gears are of uniform cross section throughout their length. Certain modified hobbing processes have been suggested for the cutting of bevel gears but without the use of a helical cutter. Also, the theoretical possibility of cutting a spiral bevel gear by a tapering helical hob of changing pitch has been recognized, but the mechanical difficulties involved in the accurate manufacturing of such a hob are such as to render it of no practical utility.

One of the objects of the present invention is the provision of a method for accurately producing teeth upon conical gear blanks by a continuous operation, wherein a tool, preferably a hob, of simple construction is employed and the tool and gear blank are given a simple relative movement.

This method has been found the means of producing a new type of bevel gear having lengthwise curved or spiral teeth and it is in connection with the production of this gear that I shall describe my process. The gear itself is the subject of a separate ap-

plication as is also the tool employed by me in the production of this gear. The present invention is confined to a process for producing gears.

For the purpose of describing my invention reference is had to the accompanying drawing wherein for the sake of illustration I have shown the principles and instrumentalities employed in the production of the new spiral bevel gear, it being understood, however, that my invention is not confined to the specific embodiment illustrated, but is capable of modification within the scope of the invention and the limits of the appended claims.

In the drawings:

Figures 1 to 7 show diagrammatically the geometrical principles involved.

Figure 8 is a sectional elevation showing the hob in engagement with the gear blank;

Figure 9 is a pitch cone development of the hob;

Figures 10 and 11 are diagrammatic views showing respectively the plan and side elevation of the hob and gear blank in cooperative relation.

Figure 12 is a diagrammatic view illustrating geometrically the relationship of an Archimedean spiral and an abridged involute.

To understand the invention, it is necessary first to refer to the basic principle involved. As is well known, a bevel gear may be regarded as a development from a segment of an annular rack or crown gear; also, all gears which are developed from the same crown gear, whatever the angle of the bevel will run in mesh with each other. The usual type of spiral bevel gear forms in its development in the crown gear a series of non-parallel curves. There is also a type of spiral bevel gear, the longitudinal curves of the teeth of which are involutes of a circle and are therefore parallel. Neither of these types can be generated by a hobbing process employing a simple helical hob.

I have discovered, however, that by employing a tool of predetermined construction, preferably a tapering hob of constant

lead, and by positioning same in predetermined relation to a conical gear blank and by imparting a predetermined relative movement between gear blank and tool, teeth can be produced upon the blank with accuracy and without mutilation and by a continuous process. The settings and movements preferred lend themselves to the quick and accurate production of a new type of spiral or curved tooth bevel gear and it is in connection with the production of this gear that I shall describe my process.

The geometrical principles involved in this discovery will be readily understood from the following: Figure 1 represents an involute of a circle which is regarded as generated by a point a on a string b , which is unwound from a base circle or drum c and traces the curve d . If the point a is offset from the string, either outwardly or inwardly, but maintained in fixed relation thereto, the trace of such offset point will be a modified involute. As shown in Figure 2 the point a' is outwardly offset and will trace a curve e which may be termed an extended involute. In Fig. 3 the point a^2 is inwardly offset and will trace a curve f , which may be termed an abridged involute. If, as shown in Fig. 4, the degree of abridgment or inward offsetting of the point is such as to make it initially coincide with the center of the base circle, the abridged involute curve f' which is traced, will be a true Archimedean spiral.

That the abridged involute reduces to an Archimedean spiral when the abridgment is numerically equal to the radius of the base circle, is readily seen from Fig. 12. A point P of the line t describes a common involute s when said line rolls on the circumference of the circle c . Owing to the method of generation, the line t is always a normal of the involute s , and the momentary center of curvature is at Q . The length of the line PQ is equal to the length of the developed arc RQ which, in turn is equal to $r_0 \varphi$, if r_0 denotes the radius of the base circle. To construct a point P_1 of the Archimedean spiral, a perpendicular PP_1 is erected at P , and the distance PP_1 is made equal to $OQ = r_0$. It follows that the quadrangle $OQPP_1$ is a rectangle because $OQ = P_1P$ and the angles OQP and QPP_1 are both right angles. Hence the radius vector of the Archimedean spiral $OP_1 = QP = r_0 \varphi$. It is also evident that the vectorial angle of the spiral $\varphi' = \varphi$, because the side SO is perpendicular to OR , and OP_1 to OQ . Therefore: $OP_1 = r_0 \varphi'$ or the radius vector is proportional to the vectorial angle, which is the definition of an Archimedean spiral. In this connection it is to be noted that the line P_1Q is a normal of the spiral s_1 , because Q is the center of

instantaneous rotation both for P and P_1 . A circular arc struck from Q with a radius QP_1 is, therefore, tangent to the spiral s_1 at P_1 .

As shown in Figure 5, a rigid parallelogram g is substituted for the string and is rolled around the circle c without sliding. If a circle c' concentric to the circle c is drawn so as to be tangent to the other side g' of the parallelogram g , then in the rolling of said parallelogram without sliding about the base circle c , the outer side g' will both roll and slide upon the circle c' . Thus a series of equi-distant points $h, h', \dots$, on the outer line g' of the parallelogram will, in the rolling of said parallelogram as just described, trace a series of extended involute curves $e', e^2, \dots$, as indicated in Fig. 5, which may be regarded as generated either by said parallelogram, rolling upon the circle c , or by points in the line g' rolling and uniformly sliding upon the circle c' . If, from the points $h', h^2, h^3, \dots$, lines i, i', i^2 be drawn to the point j (the point of tangency of the parallelogram with the circle c as shown in Fig. 5), such lines will be respectively normal to the curves $e^2, e^3, e^4, \dots$, since because of the method of construction the points $h', h^2, h^3, \dots$, momentarily rotate about the point j as a center. A similar relation will exist between the normals drawn from all points in the generated curves which lie in a line tangent to the circle c' , said normals all passing through a common point which is the intersection with the base circle c of the radius k from the point of tangency of the line g' in the circle c' .

In Figure 6 a base circle 1 of smaller radius than the circle c is arranged tangent to the latter at the point of tangency of the parallelogram g . If the parallelogram is rolled about the smaller circle, the points $h, h', \dots$, will trace another series of modified involute curves which are, however, respectively tangent to the curves $e', e^2, \dots$, because the normals of the superposed point $h', h^2, \dots$, all pass through the point j the common instantaneous center of rotation for both systems. If a second parallelogram m exactly similar to the parallelogram g is arranged to extend inward from the point of tangency j , then the series of equi-distant points $m, m^2, \dots$, corresponding to the points $h, h', \dots$, will in the rolling of this parallelogram about either the circle c or the circle 1 trace a series of abridged involute curves. If the radius of the circle 1 is equal to the width of the parallelogram then the points $m, m^2, \dots$, will trace curves which are Archimedean spirals.

In Figure 7 the parallelogram m is swung about the point j to a position where it coincides with the parallelogram g , this bring-

ing the base circle 1 to the outside of the base circle c and tangent thereto at the point j . In this position the Archimedean spiral curves n^1 , n^2 , etc., will be tangent to the curves e^1 , e^2 , etc.

It will be evident from the above that any series of modified involute curves generated by points in a line parallel to, but offset from a line tangent to the base circle can be arranged respectively in tangent relation to any other series of modified involute curves generated by equally spaced points in an equally offset line tangent either to the same base circle or to a base circle of greater or smaller diameter, the line being offset either outwardly or inwardly from the base circle. Most important, however, it is evident that a series of Archimedean spiral curves so generated can be arranged in tangent relation to any other similar series of modified involute curves. Therefore, it is mathematically possible, as will be hereinafter set forth, to generate a spiral bevel gear, the teeth of which are of longitudinally modified involute curvature, by means of a hob which is a development of a simple Archimedean spiral.

The mathematical principle which makes possible the production of the new gears according to my invention may be briefly stated as follows: I have discovered a relationship between the modified involutes on one hand, and the Archimedean spiral on the other, in that both are tangential or what might be termed, asymptotic curves to a common involute. Being tangential curves they are subject to the well known mathematical rule that a normal to a tangential curve at any point must pass through the center of curvature, (point Q in Figure 12) of the corresponding point of the parent curve. (See Scheffers' Theorie der Kurven, 2nd edition, p. 99.)

It is a property of common involutes that the generating line is always perpendicular to the curve itself, while the center of curvature coincides with the point of tangency of said line with the base circle. From this follows that a series of involutes such as might be generated by a number of equi-spaced points of a straight line, are all parallel and have a common center of curvature at every instant. I constructed, therefore, two series of tangential curves, modified involutes and Archimedean spirals respectively, from two corresponding parent series of common involutes by using as a generator a rack of constant pitch and infinitesimal thickness. Said rack does not intersect the generated curves at right angles (as is the case with common involutes) but at variable acute angles hh^1j , hh^2j , hh^3j , etc., Figure 6, resulting in a gradual increase of the normal pitch, that is, an outward

divergence of said curves. However, all normals along the generator meet in the same point j , Figure 7, for both series; in other words, the corresponding curves h^1m^1 , h^2m^2 , etc., are tangent and do not interfere with each other in the immediate neighborhood of the generating line g^1 . It is true that there is a secondary crossing or interference between the corresponding curves of the two series further away, but that interference is only apparent and would take place only if both the hob and the gear to be cut were plane developments, that is, crown gears. However, the hob which I am using is pinion shaped, and the cone angle and the pressure angle of teeth are so selected that no secondary interference occurs even when a crown gear is being cut.

There are four requirements which have to be met in devising a practical method for producing curved tooth gears from conical blanks by a continuous process. First, the tool or hob should be of such shape that it will finish both sides of the tooth and "clear" the concave sides. This requirement I find best satisfied in a taper hob. Second; the hob should be of a construction such as will lend itself to rapid and accurate production. The hob, therefore, should preferably be produced by means of machinery employing gear trains and other elements of a constant ratio only. Third; the process itself of producing the gears should preferably also be accomplished by constant ratio elements, such as gearing, slides, etc., because these will lend themselves more readily to accomplishing the motions desired. Fourth, the finished gear must satisfy certain practical requirements as to strength of teeth, width of face, helical angle, pressure angle, etc. From those four premises the present method was evolved.

In Figure 8 A illustrates a tapering hob having a longitudinal rack section of constant pitch in engagement with the improved spiral gear.

Figure 9 shows a development of the pitch cone of this hob, and, as shown, the successive threads B , B' , etc., are Archimedean spiral curves. C is a center corresponding to the apex of the cone, and D is a radius drawn from this center and crossing the curves. E , E' , etc., are lines drawn from the points of intersection in the radius D of the successive curves and respectively normal to said curves. All of these lines will meet in a common point F , which is a predetermined distance from the center C according to the pitch of the spiral curves and which is known as the "polar sub-normal."

It is evident that this Fig. 9 corresponds to that shown in Fig. 7 and if the spacing of the curves is the same and the distance of the polar sub-normal from the center is

equal to the offsetting of the point h from the circle C , the two figures can be superposed with the curves of the one tangent to or matching the curves of the other along the line g' . Along this line the hob whose threads are diagrammatically represented at n' , n^2 and n^3 in this figure, and the crown gear of the system, whose base circle is c and whose teeth are diagrammatically represented at e' , e^2 and e^3 are of rack section and of constant pitch. When superposed the base circles of hob and the crown gear, which also represents a development of the gear to be produced, are tangent and the 15 normals to the curves of both at the pitch surfaces along the rack element g' will intersect in the same point h . In this arrangement, moreover, the hob apex h the blank apex which lies at the center of the base 20 circle C and the point of intersection of the perpendiculars j will all lie in the same straight line.

The hob shown in Fig. 8 is longitudinally slotted or gashed, as indicated at G , which 25 in effect, forms thereof a series of rack cutters arranged in spiral relation to each other. Thus by relatively arranging the hob or cutter and the gear blank so as to be tangent to a common plane and in the relation indicated in Fig. 7 and by relatively 30 rotating the hob and cutter and also imparting a movement of translation about the center of the base circle, gear teeth which are longitudinally non-parallel and 35 of modified involute curvature will be developed.

In the practical method of manufacturing 40 these new gears, the hobs are first formed with reference to the pitch of the gears to be cut. The hob blanks are of preferably truncated conical form, the cone angle being between 20° and 45° , but preferably of 30° . The cross section and lead of the helical 45 thread is determined by the pitch of the gears to be cut and also by whether a single or multiple thread is used. The length of the hob and the distance from the apex of the cone is also selected with respect to the particular work to be performed.

50 The operations required when cutting the new type gear are, first, the setting of the hob and the gear blank so that their pitch cones are tangent to a common plane, the axis of the hob being spaced from the calculated base circle of the gear or the base 55 circle c of the basic crown gear, as diagrammatically illustrated in Fig. 7, by a distance equal to the polar sub-normal of the hob and the apex of the cone being in the radial line which passes through the 60 imaginary point of tangency to the base circle, as indicated in Figs. 10 and 11. After the setting of the hob and blank, rotational movement is imparted thereto and the 65 ratio is such that each revolution of the hob

will advance either one tooth of the gear or an exact multiple thereof. A relative movement of translation is given to the blank and cutter, preferably in the manner of a crown gear meshing with the gear to be produced, around an axis, which passes through the pitch cone of the blank and which is perpendicular to the tangent plane. This will cause the cutter to progressively 70 be fed into engagement with the blank and across the face thereof, thereby tracing the longitudinal contour of the teeth, while at the same time the rotational movement of the blank and cutter will develop the cross-sectional contour thereof. When complete, the gear will be of a form which will run in perfect mesh with any other gear formed by a similar cutter or hob but of the opposite hand. Thus a right-hand 75 hob will cut a left-hand gear and a left-hand hob a right-hand gear, or vice versa, but if the polar sub-normals and the relative setting is the same, the gears will exactly 80 mesh.

As previously stated, the important feature 85 of my method is that a hob of constant lead preferably tapering is used instead of the complex constructions which have heretofore been suggested. Furthermore, I have discovered that by this method gears may 90 be cut without mutilation, whereas in all other attempts at hobbing spiral bevel gears employing a tool having a continuous 95 thread, the teeth thereof have been more or less mutilated.

The method or process which forms the 100 subject of this invention may be practiced in various ways without departing from the intent of the invention or the scope of the following claims, and this application is 105 intended to cover any variations, uses, or adaptations thereof, following, in general, the principles of the invention and including such departures from the present disclosure as come within known or customary 110 practice in gear cutting and may be applied to the essential features hereinbefore set forth and as fall within the limits of the appended claims.

Having thus described my invention, what 115 I claim is:

1. The method of generating spiral bevel 120 gears having teeth which are longitudinally non-parallel and of modified involute form, which consists in selecting a tapering spiral hob of a form which may be generated by the movement of a rack element of constant pitch in acute angular relation to the curves, in relatively rotating the hob and the gear blank in predetermined timed 125 relation and in also imparting a relative movement of translation about the apex of the pitch cone of the blank.

2. The method of generating spiral bevel 130 gears having teeth which are longitudinally

non-parallel and of modified involute form, which consists in selecting a tapering spiral hob of substantially constant axial pitch, relatively rotating the hob and the gear blank in predetermined timed relation to each other and in imparting a relative movement of translation concentric to the apex of the pitch cone of the blank.

3. The method of generating spiral bevel gears having teeth which are longitudinally non-parallel and of modified involute form, which consists in selecting a tapering spiral hob of a form which in development, is an Archimedean spiral having a predetermined relation to the development of the selected tooth curve, such relation being that the polar sub-normal of the spiral is equal to the distance of the generating point from the line rolling on the base circle of the selected curve.

4. The method of generating spiral bevel gears having teeth which are longitudinally of modified involute form and non-parallel, which method consists in selecting a tapering helical hob forming in development a series of modified involute curves, the modification of said curves having a predetermined relation to the modification of the longitudinal tooth curves of the gear to be generated; in relatively rotating the hob and gear blank in predetermined timed relation and in imparting a relative movement of translation concentric to an axis passing through the apex of the pitch cone of the blank.

5. The method of generating spiral bevel gears having teeth which are longitudinally of modified involute form and are non-parallel consisting in selecting a tapering spiral hob of constant axial pitch and which in development forms an Archimedean spiral having a predetermined polar sub-normal in setting said hob in relation to the gear blank so that the pitch cones thereof will be tangent to a common plane with the imaginary apex of the hob cone perpendicular to a radius of the imaginary base circle for the gear and spaced from a line tangent to said base circle at the intersection of said radius by a distance equal to the polar sub-normal of the spiral; in relatively rotating the hob and the gear blank in timed relation to each other and in imparting a movement of translation to the hob concentric to the base circle of the gear blank.

6. The method of generating spiral bevel gears having teeth which are longitudinally spirals of the general involute type, which consists in selecting a tapering hob, the thread or threads of which are also longitudinally spirals of the general involute type, the latter having a different base radius but the same modification in absolute value as the former, in relatively rotating the hob and the gear blank in prede-

termined timed relation and in also imparting a relative movement of feed across the face of the blank.

7. The method of generating spiral bevel gears having teeth which are longitudinally spirals of the general involute type, which consists in selecting a tapering hob of a form which may be generated by the movement of a rack element of constant pitch along a geodesic line, in relatively rotating the hob and the gear blank in predetermined timed relation, and in also imparting a relative movement of feed about the apex of the pitch cone of the blank.

8. The method of generating spiral bevel gears having teeth which are longitudinally of modified involute form, which method consists in selecting a tapering helical hob forming in development a series of modified involute curves, the modification of said curves having a predetermined relation to the modification of the longitudinal tooth curves of the gear to be generated; in relatively rotating the hob and gear blank in predetermined timed relation and in imparting a relative movement of translation concentric to an axis passing through the apex of the pitch cone of the blank.

9. The method of producing curved teeth on conical blanks which includes rotating a taper hob in engagement with a continuously rotating blank and imparting an additional relative rolling movement between the hob and blank.

10. The method of producing curved teeth on conical blanks which includes rotating a taper hob in engagement with a continuously rotating blank and imparting an additional relative movement between the hob and blank about the apex of the blank to generate the teeth thereon.

11. The method of producing teeth on conical blanks which includes rotating a hob of constant lead in engagement with a continuously rotating blank, while imparting an additional relative movement between the hob and blank to generate the teeth.

12. The method of producing teeth on conical blanks which includes rotating a hob of constant lead in engagement with a continuously rotating blank while imparting an additional relative movement between the hob and blank, about the apex of the blank, to generate the teeth.

13. The method of producing gears from conical blanks which includes rotating a hob having uniform pitch in axial section in engagement with a continuously rotating blank, while imparting an additional relative movement between the hob and blank in the manner of a gear in mesh with a crown gear, to generate the teeth.

14. The method of producing gears which consists in rotating a taper hob in engagement with a continuously rotating gear

- blank while imparting an additional relative movement between the hob and blank in the manner of a gear in mesh with a crown gear, to generate the teeth.
- 5 15. The method of producing gears from conical blanks which consists in positioning a taper hob diagonally across the face of the gear blank, and rotating the hob and blank in intermeshing timed relation.
- 10 16. The method of producing gears from conical blanks, which consists in positioning a hob of constant lead diagonally across the face of the gear blank, and rotating the hob and blank in intermeshing timed relation.
- 15 17. The method of producing gears from conical blanks which includes positioning a taper hob diagonally across the face of the gear blank, rotating the hob and blank in intermeshing timed relation and relatively 20 moving the hob and blank about the apex of the blank.
18. The method of producing gears from conical blanks which includes positioning a hob of constant lead diagonally across the 25 face of the gear blank, rotating the hob and blank in intermeshing timed relation and relatively moving the hob and blank about the apex of the blank.
19. The method of producing gears which 30 consists in revolving a taper hob and a gear blank in intermeshing relation with the pitch surfaces of hob and blank tangent to a common plane, producing a relative rolling motion between the blank and hob to generate the teeth and simultaneously imparting a continuous indexing movement to the blank.
20. The method of producing a gear which 35 consists in revolving a hob of constant lead and a gear blank in intermeshing relation with the pitch surfaces of hob and blank tangent to a common plane, producing a relative rolling motion between the blank and hob to generate the teeth and simultaneously imparting a continuous indexing movement 40 to the blank.
21. The method of producing teeth on conical blanks which consists in rotating a taper hob in intermeshing relation with a 45 rotating blank and generating the profiles of the teeth on the blank by an additional movement between the hob and blank in which the hob is swung bodily about the axis of the crown gear with which the blank is theoretically rolling.
- 55 22. The method of producing teeth on conical blanks which consists in rotating a hob of constant lead in intermeshing relation with a rotating blank and generating the profiles of the teeth on the blank by an 60 additional movement between the hob and blank in which the hob is swung bodily about the axis of the crown gear with which the blank is theoretically rolling.
23. The method of producing bevel gears 65 which consists in rotating a taper hob and gear blank in intermeshing relation and simultaneously swinging the hob about the gear apex at a constant radial distance therefrom.
24. The method of producing bevel gears 70 which consists in rotating a hob of constant lead and a gear blank in intermeshing relation and simultaneously swinging the hob about the gear apex at a constant radial distance therefrom.
- 75 25. The method of producing curved teeth on conical blanks which consists in effecting a continuous intermeshing action between a taper hob and a gear blank to produce cutting and continuous indexing, and generating the tooth profiles by effecting a relative rolling motion between the hob and blank in the manner of a crown gear in mesh with the gear to be cut, said relative rolling motion, in addition to generating the profile of the 80 teeth, acting also to move the hob so that full depth of the teeth is cut at all points on the face width of the gear without any radial displacement of hob relatively to the cone apex of the gear.
- 85 26. The method of producing curved teeth on conical blanks which consists in effecting a continuous intermeshing action between a hob of constant lead and a gear blank to produce cutting and continuous indexing, and generating the tooth profiles by effecting a relative rolling motion between the hob and blank in the manner of a crown gear in mesh with the gear to be cut, said relative 90 rolling motion, in addition to generating the profiles of the teeth, acting also to move the hob so that full depth of the teeth is cut at all points on the face width of the gear without any radial displacement of the cone apex of the gear.
- 95 27. The method of producing gears adapted to mesh interchangeably with a basic crown gear which consists in rotating a taper hob and blank continuously about their respective axes while maintaining the hob apex in definite offset relation to the apex of the crown gear and imparting an additional relative movement between the hob and blank about the axis of the crown gear to generate the profiles of the teeth.
- 100 28. The method of producing gears adapted to mesh interchangeably with a basic crown gear which consists in rotating a taper hob of constant lead and a gear blank continuously about their respective axes, 105 while maintaining the hob apex in definite offset relation to the apex of the crown gear, and imparting an additional relative movement between the hob and blank about the axis of the crown gear to generate the profiles of the teeth.
- 110 29. The method of producing gears which consists in positioning a taper hob and blank so that their pitch surfaces are tangent to a common plane, with the axis of the hob,
- 115 120 125 130

projected into the tangent plane, perpendicular to a line connecting the hob and gear apices, and rotating the hob and blank in intermeshing timed relation and imparting 5 an additional relative motion therebetween to generate the teeth on the blank.

30. The method of producing gears adapted to mesh interchangeably with a basic crown gear which consists in positioning a 10 hob, the normals to whose threads at the pitch surface in development intersect in a common point, so that this point will be on the base circle of the crown gear, rotating the hob and blank in intermeshing relation 15 about their respective axes and imparting an additional relative movement between the hob and blank about the axis of the crown gear.

31. The method of producing gears which 20 consists in positioning a hob and blank so that normals to the hob threads and the teeth to be produced on the blank along a line lying in the surfaces of both hob and blank in development intersect in a single 25 point, and rotating the hob and blank in timed relation.

32. The method of producing gears which consists in positioning a hob and blank so that normals to the hob threads and the teeth 30 to be produced on the blank along a line lying in the surfaces of both hob and blank in development intersect in a single point, and rotating the hob and blank in timed 35 relation and imparting an additional relative movement therebetween.

33. The method of producing gears which consists in positioning a hob and a gear blank so that in development their base circles are tangent, rotating the hob and blank 40 continuously about their respective axes in intermeshing relation and imparting an additional relative movement between the hob and blank to generate the teeth on the blank.

34. The method of generating gears which 45 consists in positioning a hob in relation to the gear blank so that the pitch surfaces thereof will be tangent to a common plane, and the base circles of their respective developments touch each other, in relatively 50 rotating the hob and gear in intermeshing timed relation and imparting a relative movement of translation to the hob concentric to an axis passing through the apex of the blank.

35. The method of producing gears which consists in rotating a hob and blank about 55 their axes at a ratio directly proportional to the radii of their base circle in development and simultaneously imparting an additional 60 relative movement between hob and blank to generate the teeth on the blank.

36. The method of producing gears which consists in selecting a taper hob, the perpendiculars to whose thread along the 65 generatrix of the pitch surface of the hob in-

tersect in a point, positioning the hob and a conical gear blank so that in development the hob apex, the blank apex and the point of intersection of the perpendiculars all lie in the same straight line and rotating the 70 hob and blank in timed relation.

37. The method of producing gears which consists in selecting a taper hob, the perpendiculars to whose thread along the generatrix of the pitch surface of the hob intersect 75 in a point, positioning the hob and a conical gear blank so that in development the hob apex, the blank apex and the point of intersection of the perpendiculars all lie in the same straight line, and rotating the hob and blank in timed relation and imparting an 80 additional relative movement therebetween to generate the teeth on the blank.

38. The method of producing gears adapted to mesh interchangeably with a basic crown gear whose teeth have a constant pitch along a straight line offset from its apex which consists in selecting a hob capable of meshing with a crown gear along 85 such line, and rotating the hob and blank in intermeshing timed relation and imparting an additional relative movement therebetween to generate the teeth on the blank.

39. The method of producing gears adapted to mesh interchangeably with a basic crown gear which consists in employing a taper hob, capable of meshing with the crown gear along a line of action passing through the apex of the hob, and rotating the hob and a gear blank in intermeshing 90 timed relation and imparting an additional relative movement therebetween to generate the teeth on the blank.

40. The method of producing gears having longitudinally curved teeth which consists in employing a hob whose pitch lines and the pitch lines of the gear to be produced in development are tangent at their intersection with the generatrix of the pitch 95 surface of the hob, and rotating the hob and a gear blank in timed relation.

41. The method of producing gears having longitudinally curved teeth which consists in employing a hob whose pitch lines and the pitch lines of the gear to be produced in development are tangent at their intersection with the generatrix of the pitch 100 surface of the hob, rotating the hob and a gear blank in timed relation and imparting an additional relative movement therebetween.

42. The method of producing gears adapted to mesh interchangeably with a basic crown gear which consists in employing a hob whose pitch lines match those of the crown gear along a straight contact line between the pitch surface of the hob and crown gear, and rotating the hob and a gear blank in timed relation.

43. The method of producing gears adapt-

ed to mesh interchangeably with a basic crown gear which consists in employing a hob whose pitch lines match those of the crown gear along a straight contact line 5 between the pitch surface of hob and crown gear, rotating the hob and a gear blank in timed relation and imparting an additional relative movement therebetween to generate teeth on the blank.

10 44. The method of producing gears adapted to mesh interchangeably with a basic crown gear which consists in employing a hob whose pitch lines match those of the crown gear along the projection of the hob 15 axis in the plane of the crown gear and rotating the hob and a gear blank in timed relation and imparting an additional relative movement therebetween to generate teeth on the blank.

20 45. The method of producing gears adapted to mesh interchangeably with a basic crown gear which consists in employing a hob whose pitch lines match those of the crown gear along the projection of the hob 25 axis in the plane of the crown gear and rotating the hob and a gear blank in timed relation.

46. The method of generating spiral bevel gears having teeth which are longitudinally 30 spirals of the general involute type, which consists in selecting a hob, the thread or threads of which are also longitudinally spirals of the general involute type, in relatively rotating the hob and blank in predetermined timed relation and in also imparting a relative movement of feed across the face of the blank.

47. The method of producing gears which consists in positioning a taper hob and 40 blank with their pitch surfaces tangent to a common plane, rotating hob and blank in intermeshing relation about their respective axes and imparting an additional relative movement between hob and blank about an 45 axis perpendicular to said common plane.

48. The method of producing gears which consists in selecting a hob whose thread in development is an Archimedean spiral, in 50 positioning the hob and a gear blank so that their pitch surfaces are tangent to a common plane and in rotating the hob and blank in intermeshing relation.

55 49. The method of producing gears which consists in selecting a hob whose thread in development is an Archimedean spiral, in 55 positioning the hob and a gear blank so that their pitch surfaces are tangent to a common plane and in rotating the hob and blank in intermeshing timed relation, while imparting an additional relative generating movement between hob and blank.

50. The method of producing gears which consists in selecting a hob which in development 60 forms a series of modified involute curves, in positioning the hob and a gear

blank so that their pitch surfaces are tangent to a common plane and in rotating the hob and blank in timed relation.

51. The method of producing gears which consists in selecting a hob which in development 70 forms a series of modified involute curves, in positioning the hob and a gear blank so that their pitch surfaces are tangent to a common plane and in rotating the hob and blank in timed relation while imparting an additional relative generating movement between the hob and blank. 75

52. The method of producing gears which consists in selecting a hob having a thread of constant pitch which in development 80 forms a series of modified involute curves, in positioning the hob and a gear blank so that their pitch surfaces are tangent to a common plane and in rotating the hob and blank in timed relation. 85

53. The method of producing gears which consists in selecting a hob having a thread of constant pitch which in development 90 forms a series of modified involute curves, in positioning the hob and a gear blank so that their pitch surfaces are tangent to a common plane and in rotating the hob and blank in timed relation while imparting an additional relative generating movement between the hob and blank. 95

54. The method of generating gears having teeth which are longitudinally spirals of the general involute type which consists in selecting a hob, the thread or threads of which are also longitudinally spirals of the general involute type, in relatively rotating the hob and a gear blank in predetermined timed relation and in imparting an additional relative movement between hob and blank about the apex of the pitch cone of the blank. 100

55. The method of producing gears having teeth which are longitudinally spirals of the general involute type, which consists in selecting a taper hob, the thread or threads of which are also longitudinally spirals of the general involute type, in relatively rotating the hob and a gear blank in predetermined timed relation and in imparting an additional relative movement between hob and blank about the apex of the pitch cone of the blank. 110

56. The method of generating gears which consists in selecting a hob the thread or threads of which are longitudinally spirals of the general involute type in rotating the hob and a gear blank in intermeshing timed relation while imparting an additional relative movement between hob and blank to generate the teeth on the blank. 120

57. The method of generating gears which consists in selecting a taper hob the thread or threads of which are longitudinally spirals of the general involute type in rotating hob and blank in intermeshing timed relation. 130

58. The method of producing teeth on conical blanks which includes rotating a tool, having an effective cutting portion of rack and section and of constant pitch in continuous intermeshing engagement with a continuously rotating blank while imparting an additional relative movement between the tool and blank to generate the teeth on the blank.
59. The method of producing teeth on conical blanks which consists in rotating a plurality of tools arranged on a cone in continuous intermeshing engagement with a
- rotating gear blank while imparting an additional relative movement between tools and blank to generate the teeth on the blank.
60. The method of producing gears which consists in rotating a plurality of tools, arranged at a progressively increasing distance from a common axis of rotation, in continuous intermeshing engagement with a rotating gear blank while imparting an additional relative movement between tools and blank to generate the teeth on the blank.
